UNITED STATES PATENT OFFICE.

FRIEDRICH EMIL KRAUSS, OF SCHWARZENBERG, GERMANY.

CARTRIDGE FOR FIRE EXTINGUISHERS AND THE LIKE.

Application filed November 7, 1923, Serial No. 673,365, and in Germany August 12, 1922.

This invention relates to a gas-developing cartridge, particularly for fire extinguishers, which operates independent from the extinguishing or other liquid and in which the substances serving for the generation of the gas, one of which is preferably in the dry state, in order to save space, are arranged concentrically. The improved cartridge is so constructed that the container for the acid or the like is opened with absolute certainty and a choking of the cartridge itself is prevented. The ejection of the products of the reaction or free acid or the like from the cartridge is furthermore entirely excluded, as well as the danger of the cartridge exploding. Inasmuch as the gas producing chemicals of the improved cartridge do not at once come into action with their total quantity, as in the known cartridges, but successively, the development of the gas also takes place gradually and in correspondence with the requirements and consequently the cartridge, which itself has a comparatively large air space, can be applied to extinguishers which for some reason or other have no air space of their own and by the application of ordinary cartridges would be exposed to the danger of an explosion.

The opening of the acid container, assuming it to be substantially cylindrical, take place by means of a destructor whose action is based on the principle of inclined planes or wedges, which is operated by a striking-pin or the like, preferably by the intercalation of a body, which is variable in its shape without suffering destruction and which renders the employment of a stuffing-box for the striking pin unnecessary and at the same time forms a seal for the cartridge, between the acid container and the striking-pin. By retaining this intermediate body other than cylindrical acid containers may equally well be opened by the striking-pin.

A choking of the cartridge itself is effectively prevented by the provision of a protective sheath and a wire gauze cylinder at some distance around the acid vessel or by the employment of granular alkali carbonate or bicarbonate or by mixing the alkali with infusorial earth, quartz, chamotte or the like. The ejection of products of conversion or free acid is prevented by an acid retainer or gas purifier or filter. This device consists of a layer of granulated alkali

carbonate or bicarbonate or other suitable substance and tablets or the like of suitable chemicals, such as alkali carbonate or bicarbonate disposed between wire gauze ⁶⁰ sieves and provided with openings serving for the regulation of the passage of the gas.

There is no danger of the cartridge itself exploding for the reason that on the one hand, as already stated above, the gas generating substances come into action only gradually and successively, and on the other hand because the cartridge is provided with a foil which must be torn. If the cartridge is thrown away or is set in action ⁶⁵ unintentionally or inadvertently by a blow, push or fall, for instance in a parcel during transit, no appreciable change can be observed externally. It merely slowly develops gases, which tear the protective foil, ⁷⁰ but no acid issues, as this is neutralized on its way to the outlet and consequently no damage can be done.

The accompanying drawing illustrates one embodiment of the invention by way of ⁸⁰ example.

Fig. 1 represents the improved cartridge in longitudinal section,

Fig. 2, an acid container so constructed that it may be opened without a special ⁸⁵ destructor, and

Fig. 3, the manner of fixing the improved cartridge within a fire extinguisher.

Referring to the drawing it will be seen, that the shell *a* of the cartridge contains ⁹⁰ in an axial arrangement an acid container *n*, made of glass, for instance, which is enclosed by a protective sheath *e* and a jacket *f* of wire gauze or the like, preferably with a little clearance. The sheath *e* is somewhat ⁹⁵ shorter than the jacket *f*, in order that after the opening of the vessel *n* the acid or the like issuing from it may first come in contact with a part of the second chemical *o* serving for the generation of the gas. This ¹⁰⁰ chemical is, for instance, an alkali carbonate or bicarbonate in the granulated state. To the lower end the shell of the cartridge is soldered a flanged sleeve *b*, so as to form a tight joint, which is provided with an annular contraction *p* and a disc *d* of such shape, that its configuration may be altered without destruction. Between this disc *d*, which may for instance, consist of a sheet of corrugated lead and the vessel or container *n* is situated a destructor *c* of suitable ¹¹⁰ shape extending over the end of the acid

5 container or bottle, which with wedge-shaped points or spikes extends into the central opening of the contracted portion p of the flanged sleeve b and which is compressed when it is forced in the direction of the bottle by a striking-pin or the like acting upon the disc d and destroys the end of the acid bottle n .

In the upper part of the cartridge in Fig. 1 an acid container or a gas purifier or filter is housed, which consists of a perforated dish g or disc which also contains or supports granulated alkali carbonate or bicarbonate and prevents any free acid from issuing. The same object is served by tablets k of alkali carbonate or the like disposed above the dish g and a perforated plate h between which gauze sieves i are arranged. These tablets or tabloids have recesses q and are so piled up that these recesses are displaced in relation to each other or staggered and thus form channels through which the gas passes and deposits any admixtures of the other chemical. The tablets are housed in a sheet-iron ring m or the like, which at the same time serves as distance piece between the perforated plate h covering the dish g and a second perforated plate g . A tinfoil disc l forms the upper seal of the cartridge.

The destructor c may be eliminated by providing the acid bottle near its lower end with a swelling or enlargement r , which, as illustrated in Fig. 2 is situated between the contracted portion p' of the flanged sleeve b' and the disc d and which is destroyed, when the striking-pin acts upon the latter.

The gas development in the lower portion of the cartridge enables bubbles of gas to enter into the bottle n' and prevents the production of a vacuum in the latter which would hinder the escape of the acid.

The gas generated after the destruction of the acid bottle ascends in the annular space formed between the sheath e and the jacket f , passes through the cleaner or filter above described, collects in the chamber s until a sufficient pressure is reached, then tears the tinfoil disc l and enters the shell 50 of the fire extinguisher or any other receptacle to be set under pressure.

As mentioned in the preamble the corrugated disc d renders the employment of a stuffing-box for the striking-pin unnecessary, inasmuch as it forms a permanent gas-tight seal even after its shape has been altered by the striking-pin. The cartridge may also be provided with a flange t , as shown in Fig. 3, by means of which it may be fixed in the charge opening of a fire extinguisher, a packing ring v being preferably inserted between the contacting parts.

The charging opening of the extinguisher is closed in the ordinary way by a cap w , which at the same time guides the striking-

pin x , which need, however, not be packed by a stuffing-box. This form of closure has one less joint requiring packing than will be found in known sealing devices and is therefore less liable to leak.

What I claim as my invention and desire to secure by Letters Patent is:

1. A gas-developing cartridge for fire-extinguishers, consisting of a substantially cylindrical closed shell a central acid bottle 75 within said shell, a short sheath around said bottle, a cylinder of wire gauze of larger diameter around said sheath and a solid chemical between said wire cylinder and said shell.

2. A gas-developing cartridge for fire-extinguishers, consisting of a substantially cylindrical closed shell, a central acid bottle within said shell, a short sheath around said bottle, a cylinder of wire gauze of larger 85 diameter around said sheath, a solid chemical between said wire cylinder and said shell and a gas drying device disposed coaxially at the discharge end of said shell.

3. A gas-developing cartridge for fire-extinguishers, consisting of a substantially cylindrical closed shell a central acid bottle within said shell, a short sheath around said bottle, a cylinder of wire gauze of larger 95 diameter around said sheath, a solid chemical between said wire cylinder and said shell and a gas drying device disposed coaxially at the discharge end of said shell, 100 said drying device consisting of a layer of loose reacting chemicals and tablets of such chemicals.

4. A gas-developing cartridge for fire-extinguishers, consisting of a substantially cylindrical closed shell, a central acid bottle within said shell, a short sheath around 105 said bottle, a cylinder of wire gauze of larger diameter around said sheath, a solid chemical between said wire cylinder and said shell and a gas drying device disposed coaxially at the discharge end of said shell, 110 said drying device consisting of a layer of loose reacting chemicals and tablets of such chemicals said tablets being disposed between wire gauze disks and provided with staggered gas passages.

5. A gas-developing cartridge for fire-extinguishers, consisting of a substantially cylindrical closed shell, a central acid bottle within said shell, a short sheath around 120 said bottle, a cylinder of wire gauze of larger diameter around said sheath, a solid chemical between said wire cylinder and said shell and a gas drying device disposed coaxially at the discharge end of said shell, 125 said drying device consisting of a layer of loose reacting chemicals and tablets of such chemicals, said tablets being disposed between wire gauze disks and provided with staggered gas passages and a disk of metal foil for closing the escape end of said shell.

6. A gas-developing cartridge for fire-extinguishers, consisting of a substantially cylindrical closed shell, a central acid bottle within said shell, a short sheath around said bottle, a cylinder of wire gauze of larger diameter around said sheath, a solid chemical between said wire cylinder and said shell and a gas drying device disposed coaxially at the discharge end of said shell, said drying device consisting of a layer of loose reacting chemicals and tablets of such chemicals, said tablets being disposed between wire gauze disks and provided with staggered gas passages, a disk of metal foil for closing the escape end of said shell and a disk adapted to be deformed by the striking-pin of the extinguisher and to destroy the said acid bottle.

7. A gas-developing cartridge for fire-extinguishers, consisting of a substantially cylindrical closed shell, a central acid bottle within said shell, a short sheath around said bottle, a cylinder of wire gauze of larger diameter around said sheath, a solid chemical between said wire cylinder and said shell and a gas drying device disposed coaxially at the discharge end of said shell, said drying device consisting of a layer of loose reacting chemicals and tablets of such chemicals, said tablets being disposed between wire gauze disks and provided with staggered gas passages, a disk of metal foil

for closing the escape end of said shell, a disk adapted to be deformed by the striking-pin of the extinguisher and a destructor upon the end of said acid bottle adapted to be acted upon by said elastic disk and to destroy said acid bottle.

8. A gas-developing cartridge for fire-extinguishers, consisting of a substantially cylindrical closed shell, a flange upon the operative end of said shell adapted to fix said shell in the extinguisher within reach of the striking-pin, a packing between said flange and the extinguisher, a central acid bottle within said shell, a short sheath around said bottle, a cylinder of wire gauze of larger diameter around said sheath, a solid chemical between said wire cylinder and said shell and a gas drying device disposed coaxially at the discharge end of said shell, said drying device consisting of a layer of loose reacting chemicals and tablets of such chemicals, said tablets being disposed between wire gauze disks and provided with staggered gas passages, a disk of metal foil for closing the escape end of said shell, a disk adapted to be deformed by the striking-pin of the extinguisher and a destructor upon the end of said acid bottle adapted to be acted upon by said elastic disk and to destroy said acid bottle.

I affix my signature.
FRIEDRICH EMIL KRAUSS.
